UNITED STATES PATENT OFFICE

149,420

DESIGN FOR AN AUTOMATIC SLIDE PROJECTOR

Edward C. Klotz, Jr., Brookfield Township, Waukesha County, Wis., assignor to Picture Recording Company, Chicago, Ill.

Application October 30, 1946, Serial No. 134,383

Term of patent 7 years

(Cl. D61—1)

To all whom it may concern:

Be it known that I, Edward C. Klotz, Jr., a citizen of the United States, residing at Brookfield township, in the county of Waukesha and State of Wisconsin, have invented a new, original, and ornamental Design for an Automatic Slide Projector, of which the following is a specification, reference being had to the accompanying drawing, forming part thereof.

The figure is a perspective view of the automatic slide projector, showing my new design, the other side of which is the same as that shown, except that the lever is omitted therefrom.

I claim:

The ornamental design for an automatic slide projector, as shown and described.

EDWARD C. KLOTZ, JR.
